(57) **CLAIM**

The ornamental design for a metal holder for garden sculpture, as shown and described.

DESCRIPTION

FIG. 1 is a top, front, right side perspective view of a metal holder for garden sculpture, showing my new design;

FIG. 2 is a bottom, left side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines are for the purpose of illustrating portions of the metal holder for garden sculpture in a use environment and form no part of the claimed design.
